GARMENT SUPPORTING DEVICE

Albert T. Van Alstyne, Three Rivers, Mich.

Application June 27, 1932, Serial No. 619,559

15 Claims. (Cl. 24—246)

This invention is a garment supporting device of the type in which the fabric of the garment is engaged by suitably sustained clamping means. One of the objects of the invention is to provide a garment supporter of simple construction, equipped with a toggle-like garment-engaging device, so constructed and arranged that while the supporter is in use, a yieldable locking tension will be maintained upon the toggle member. A further object is to provide a garment-engaging toggle device, consisting of an actuator member and a clamp member, said actuator member having friction means for creating a yieldable locking tension upon the toggle device while engaged with a garment. A further object is to provide a toggle member of the character described with simple means by which it may be readily moved to locked or unlocked position, as may be desired.

20 The invention will be hereinafter fully set forth and particularly pointed out in the claims.

In the accompanying drawing:—

Figure 1 is a view in front elevation illustrating a garment supporter constructed in accordance with the invention. Figure 2 is an enlarged longitudinal sectional view on the line 2—2, Figure 1. Figure 3 is a perspective view of the supporting frame, viewed from the rear. Figure 4 is a perspective view illustrating the toggle device, viewed from the rear. Figures 5 and 6 are front and longitudinal sectional views illustrating a slight modification. Figure 7 is a front elevation illustrating another modification.

Referring to the drawing, F designates a metal frame of approximately rectangular form, provided with a central opening bounded by two spaced apart side bars 10, and connecting end bars 11 and 12 respectively. The end bar 12 is provided with laterally spaced ears 13, preferably formed by bending over the metal, as shown. The side bars are preferably formed by bending the metal so as to provide guides or channels 14, the cross bar 11 being constructed to provide a stop, as clearly illustrated in Figure 3.

45 Operative within the opening in the frame F is member T of a toggle device, hereafter referred to as the clamp member, said member being formed of flat metal and provided at one end with lateral projections 20 slidably engaging the guides or channels 14. The other end of said clamp member is turned over to form an ear 21 which is pivotally engaged by the other member T' of the toggle device. The last mentioned member T' is preferably formed of a single piece of spring wire bent to provide a loop

having a strap-engaging portion 26, and bearing portions 27, said bearing portions being rotatively mounted in the bent over ears 13 of the frame, leaving two arms of the wire projecting toward each other. Said arms are provided with return bends at positions between the ears 13, to provide two curved resilient abutment members 28, which are normally in contact with each other. The arms of the wire member T' diverge laterally from the bends 28, so as to provide portions 10 straddling the end of clamp member T, the extremities 28 of said diverging portions being bent inwardly and extended into the ends of the bearing sleeve 21, and thereby provide a pivotal connection between the members T and T'. By 15 means of this arrangement the member T', which may be termed the actuator member will pivot in the sleeves 13, and the two members T and T' will pivot with respect to each other, by means of the sleeve 21 and bent extremities 29, the 20 clamp member T being retained in slidable engagement with the frame by means of the lugs 20 travelling in grooves 14.

In the form illustrated in Figures 1 and 2, a flexible strip 30 is provided, said strip carrying 25 a post or stud 31 at one end, the other end being removably inserted in those end portions of the channels 13 which lie adjacent to the cross bar 12. In order that ample frictional surface to engage said strip may be provided a bar 32 30 is extended across the rear side of the frame, as shown in Figure 3. If desired, the end portion of strip 30 which engages the channels 14 may be provided with a metal tip 33. The strip 30 is of such length as to hang freely and permit the post 35 or stud 31 to be inserted through the opening in the frame F adjacent to the cross bar 11, so that it may be engaged by the free edge of the clamp member T. It will be observed that the post or stud 31 is preferably of rectangular form, with 40 overhanging edges 34, so that one edge may overhang the cross bar 11 and the other edge may overhang the free end of the clamp member T while the parts are in operative relation. (See Figure 2.)

45 The post or stud 31 is preferably made entirely of rubber or other resilient material which will yield to extra pressure, and will prevent undue wear on the garment while in locked relation thereto. In addition to the foregoing, such a stud does not hurt the wearer while sitting thereon, as frequently happens with types of metal posts covered with rubber, now on the market. There being approximately no appreciable strain on the post 31, either during adjustment or while in 50 55

actual use, reenforcement thereof is not needed.

In practice, the garter G, or other suspending element is secured to the supporter by being looped around the strap-engaging portion 26 of actuator member T', in a manner well understood in the art. When it is desired to connect the device with a stocking or other garment, the operator inserts a finger beneath the frame F and presses the joint of the toggle member outwardly until the parts pass the dead center to the dotted line position, Figure 2. Due to the slidable engagement of the lugs 20 with the channels 14, the effect of this pivotal movement is to slide the free edge of the clamp member T longitudinally of the frame and away from the cross piece 11. As soon as the free edge of the member T moves out of engagement with the stud 31, said stud may be withdrawn from the opening in the frame F. A portion of the garment to be supported is then engaged with the stud, and the stud-engaged portion of the fabric is passed through the opening in the frame F and temporarily held there by the operator. By then pressing the joint of the toggle device rearwardly until it moves past the dead center position to the full line position, Figure 2, the member T is so adjusted that its free edge is brought into engagement with the stud-engaged fabric, the slidable movement of the clamp member being arrested when said edge presses the stud against the stop 15. It will be observed that the portion of member T' between where it is pivotally connected with cross bar 12 and its pivotal connection with member T, plus the length of member T, plus the thickness of the stem of the post 31 is longer than the distance between cross bar 11 and the point at which the member T' is pivotally connected with cross bar 12. Therefore, when the toggle member assumes the full line position of Figure 2, the reaction resulting from the abutting of the edge of member T against the stud, causes a slight expansion of the wire body of the member T', thereby laterally moving the abutment members 28 toward each other, so that they will engage with a resilient pressure to provide a yieldable tension which tends to hold the toggle members in said full line position of Figure 2, i. e. with the clamp member T firmly gripping the fabric between it and the post 31. Thus, fabrics of different thicknesses may be used with equalized pressure or effectiveness. To disengage, the actuator member T should be operated so as to move the parts to the first mentioned dotted line position, whereupon the clamp member T will be withdrawn from engagement with the post 32.

If desired, the flexible strip 30 and the post or stud 32 may be dispensed with, as shown in Figures 5 and 6. In this form the frame F' is somewhat shorter than the frame F illustrated in the other figures, and the cross bar 11^a is provided with a groove 15^a therein, into which the free edge of the toggle member T is adapted to fit. In use, the garment or other article to be supported is inserted between and firmly gripped by the free edge of the clamp member T pressing into the grooved portion of the cross bar 11^a.

Referring to Figure 7, F² designates an approximately rectangular frame, provided with the spaced apart side bars or guides 10^a and an end bar 11^a, similar in construction to the previously described frame F.

Operatively mounted within frame F² is the clamp member T² of a toggle device, preferably of flat metal and provided near one end with pins or lugs 20^a slidably engaging the guides 10^a.

The other end of the clamp member T² is turned over, as indicated at 21^a to pivotally engage a loop-like toggle member T^x. Said member T^x is preferably constructed as an endless loop of spring wire formed with parallel arms 28^a connected by arcuate end portions 29^a. One arm 28^a is engaged by the turned over portion 21^a and the other arm 28^a is similarly engaged by a turned over portion 27^a of the frame F². Said arcuate portions are also bent inwardly as indicated at 29^x to extend into the opening formed in the frame F², so that the joint between members T² and T^x will lie within said opening while the parts are in locked position.

The frame F² is provided in suitable manner with a strap-engaging loop L, which for purposes of illustration is shown pivotally connected to a pair of turned over portions 13^a on the end of said frame, contiguous to the part 27^a.

In practice, when it is desired to connect the device with a stocking or other garment, the operator places a finger beneath frame F² and presses outwardly at the joint between members T² and T^x until the joint passes the dead center. The member T² will thus be moved to unlocked position. The fabric is then engaged with the stud 31 and said stud inserted through the frame in a manner already described. By then pressing the toggle joint in the reverse direction until the member T² engages the stud, the joint will have passed the dead center, and in so doing the pressure upon the ends of the toggle members due to the resistance of stud 31, will force the arms 28^a slightly toward each other, causing the curved portions 29^a to maintain a resilient locking tension on the parts until moved to unlocked position to release said tension, through pressure applied at the rear. By this arrangement any direct longitudinal pull on the device by reason of the increase of the spring tension created by such pull, will tend to more firmly maintain the parts in locked position.

The advantages of the invention will be readily apparent to those skilled in the art to which it belongs. For instance, it will be noted that a simple, toggle-like member is employed to clamp the garment, and that the same is so arranged that the normal tension applied to the toggle device while in locked position, will be converted into a yieldable force normally acting to prevent a breaking of the toggle, and so will maintain the parts in locked position against accidental disengagement, without strain upon the fabric or the post. Yet, when disengagement is desired, it may be readily accomplished by a very slight outward pressure applied to the toggle joint. Thus, the parts are easily manipulated and yet positively prevented from accidental disengagement. A further important advantage is that the actuator member may be readily constructed so as to inherently provide the desired locking tension upon the parts. Another advantage is that the device is of simple and inexpensive construction and not liable to readily get out of order or to become deranged and is free of sharp edges and protuberances which might wear fabrics or injure the flesh of the wearer.

Having thus explained the nature of the invention and described an operative manner of constructing and using the same, although without attempting to set forth all of the forms in which it may be made, or all of the forms of its use, what is claimed is:—

1. In a garment holder, a frame having parallel guideways, a clamp member having one end

slidably engaging said guideways, an actuator member pivotally connected to said frame, and means providing a direct pivotal engagement between said actuator member and the other end 5 of said clamp member in such manner as to provide a toggle device, said actuator member having means located between its pivotal connections with the frame and the clamp member respectively for applying a resilient locking tension to the toggle device.

2. In a garment holder of the character described, a frame having an opening therein and guideways on the opposite sides of said opening, an actuator member pivotally connected to one 10 end of said frame, a clamp member operable within said opening and having one end slidably engaging said guideways, means providing a direct pivotal engagement between the other end of the clamp member and the adjacent portion of the 15 actuator member, in such manner as to provide a toggle device, and means for maintaining a yieldable locking tension on said toggle device.

3. In a garment holder of the character described, a frame having an opening therein, an actuator member pivotally connected to one end 20 of said frame, a clamp member operable within said opening and having one end slidably engaging the frame, and means pivotally connecting the other end of the clamp member with the adjacent portion of the actuator member, so as 25 to provide a toggle device, said actuator member having yieldable abutment portions for maintaining a locking tension on said toggle device.

4. In a garment holder of the character described, a frame having an opening therein, a clamp member operating within said opening and having one end slidably engaging said frame, an actuator member formed of spring wire having bent extremities pivotally connected with the 30 other end of said clamp member, so as to provide a toggle device, means for pivotally connecting other portions of the said wire to said frame, said wire being bent to provide abutting curved portions so as to maintain a yieldable locking tension upon said toggle device.

5. In a garment holder of the character described, a frame having an opening therein, a clamp member operable within said opening and having one end slidably engaging said frame, an actuator pivotally connected with the other end 35 of said clamp member, so as to provide a toggle device, and means pivotally connecting the actuator member to said frame, said actuator member having abutting curved resilient wire portions for maintaining a yieldable locking tension on 40 said toggle device.

6. In a garment holder of the character described, a frame having an opening therein, and pivot ears at one end, an actuator member formed 45 of spring wire bent to provide arms pivotally engaging said ears, said arms being bent further to provide curved yieldably engaging abutment members, a clamp member operable within said opening and having one end pivotally engaging the extremities of said wire actuator member, so 50 as to provide a toggle device, the other end of said clamp member slidably engaging said frame, said curved abutment members acting to maintain a yieldable locking tension on said toggle device.

7. In a garment holder of the character described, a frame having an opening therein and bent over side portions providing guideways, a clamp member operable within said opening and having one end slidably engaging said guide-

ways, an actuator member pivotally connected with the other end of said clamp member, so as to provide a toggle device, means for pivotally connecting the actuator member to said frame, a flexible strip having one end in engagement with the extremities of said guideways and provided at the other end with a post adapted to extend through the opening in the frame.

8. In a garment holder of the character described, a frame having an opening therein and side bars provided with guideways on either side of said opening, a clamp member having one end slidably engaging said guideways, an actuator member pivotally connected with the other end of the clamp member so as to provide a toggle 10 device, means for pivotally connecting the actuator member to the frame, a flexible member having a metal covered edge removably engaging said guideways, said flexible member being positioned to depend in a position opposite the opening in said frame, and a post carried by the other extremity of said flexible member and adapted to pass through said opening.

9. In a garment holder of the character described, a frame having an opening therein, a clamp member operable within said opening and having one end slidably engaging said frame, an actuator member pivotally connected to the frame and also having an extension, the extremity of which is pivotally connected with the other end 20 of the clamp member in such manner as to provide a toggle device, a flexible member having one end attached to said frame, said flexible member being positioned to cover said opening, and a post attached to one face of said flexible 25 member near the other end thereof, and adapted to extend through said opening, said post being of approximate rectangular form and provided with overhanging flanges adapted to respectively engage the free edge of the clamp member and 30 the adjacent end of the frame.

10. In a garment holder, a frame having an opening therein provided with an end bar, a clamping device consisting of two members pivotally connected at one end, means providing a 35 slidable engagement between the frame and the other end of one member, means pivotally connecting the other member to the frame at a position between the ends thereof, a flexible member connected at one end to the frame adjacent the 40 pivotal connection of the last mentioned member and in such manner as to depend therefrom, and a post of solid resilient material having an integral base flange attached to one face of said 45 flexible member near the other end thereof, the body portion of said post having overhanging flanges adapted to be brought into engagement with said end bar and the free edge of the slidably engaging member of the clamping device.

11. In a garment holder of the character described, a frame having parallel guideways, a clamp member having one end slidably engaging said guideways, and a second member pivotally connected to the clamp member and also having one end pivotally connected with said frame so as to provide a toggle device, said second member having resilient means between its pivotal connections with the frame and the first member for applying a yieldable locking tension to said 55 toggle device.

12. In a garment holder of the character described, a frame having parallel guideways, a clamp member having one end slidably engaging said guideways, and a second member formed of resilient wire having a portion pivotally con- 60 65 70 75

- nected to the clamp member and another portion pivotally connected with said frame so as to provide a toggle device, said second member having resilient curved portions for applying a yieldable locking tension to said toggle device.
13. In a garment holder of the character described, a frame having an opening therein with parallel guideways on opposite sides of said opening, an end bar closing said opening at one end, a clamp member having one end slidably engaging said guideways, and a second member pivotally connected to the clamp member and also pivotally connected with said frame so as to provide a toggle device, said second member having resilient portions for applying a yieldable locking tension to said toggle device.
14. In a garment holder of the character described, a frame having parallel guideways, a clamp member having one end slidably engaging said guideways, a second member formed of an endless loop of resilient wire having a portion pivotally connected to the clamp member, and another portion pivotally connected with said frame so as to provide a toggle device, the ends of said second member being bowed to provide means for applying a yieldable locking tension to said toggle device.
15. In a garment holder, an open flat metal frame having parallel sides constructed and arranged to provide guideways, a flat metal clamp member operable between said sides and having laterally projected guide members contiguous to one end and slidably engaging said guideways, a wire member pivotally connected to said frame and having laterally projected extremities pivotally engaged with the other end of said clamp member in such manner as to provide a toggle device, and supporting means engaging said wire member.

ALBERT T. VAN ALSTYN. 20
